UNITED STATES PATENT OFFICE.

JAMES A. KINNARD, OF DETROIT, MICHIGAN, ASSIGNOR TO THE FULTON SYLPHON COMPANY, OF KNOXVILLE, TENNESSEE, A CORPORATION OF DELAWARE.

COOLING SYSTEM FOR INTERNAL-COMBUSTION ENGINES.

Application filed April 14, 1927. Serial No. 183,891.

This invention relates to cooling systems for internal combustion engines, and especially to cooling systems for the internal combustion engines of automobiles.

6 The under-hood construction and design of some makes of automobiles is not such as to enable a thermostatically-operated valve mechanism to be readily installed in the cooling system without a redesign of the structure. This fact not only retards the adoption of thermostatically-operated valve mechanism as a part of the initial equipment of such automobiles, but substantially prevents the application of thermostatically-operated valve mechanism to cars of this character which are already in service.

It is an object of this invention to provide the cooling system of an internal combustion engine with thermostatically-operated valve 20 mechanism which may be initially incorporated in the system, or subsequently applied thereto, where there is no room for such mechanism in the under-hood construction.

Another object of this invention is to provide the cooling system of an internal combustion engine with a thermostatically-operated valve mechanism which does not require any modification of the under-hood construction whether or not there is room 35 for such mechanism under the hood.

Another object of this invention is to provide the cooling system of an internal combustion engine with thermostatically-operated valve mechanism which may be incorporated within the confines of the radiator and, if desired, form a unitary part of the radiator as originally installed.

Another object of this invention is to provide the radiator of the cooling system of an internal combustion engine with thermostatically-operated valve mechanism for determining whether or not the cooling medium shall flow through said radiator.

Other objects will appear as the description of the invention proceeds.

Stated broadly, the invention comprises in combination with any suitable radiator of a cooling system for an internal combustion engine, a thermostatically-operated valve 50 mechanism, preferably of the choker type, mounted within the filler opening of the radiator and controlling the circulation of the cooling medium through the radiator.

The invention is capable of receiving a 55 variety of mechanical expressions, one of

which is shown on the accompanying drawing, but it is to be expressly understood that the drawing is for purposes of illustration only and is not to be construed as a definition of the limits of the invention, reference 60 being had to the appended claims for that purpose.

Referring to the drawing:

Fig. 1 is a schematic elevation of a cooling system for an internal combustion engine 65 of the type conventionally used on automobiles, and embodying the present invention, and

Fig. 2 is a section, on an enlarged scale, of an embodiment of the present invention. 70

Referring to Fig. 1, 10 designates any suitable internal combustion engine provided with a water jacket which communicates, through the upper water line 11, with a radiator 12 of any suitable character. The 75 radiator communicates through conduit 13 with a circulating pump 14 of any suitable character, and said pump communicates with the water jacket through the lower water line 15. While this is a conventional form 80 of cooling system commonly employed in automobiles, it is to be expressly understood that it has been selected only for the purposes of exemplification of the present invention, as the invention can be embodied in any 85 other suitable character of water circulating system, as for example, where the thermosiphon principle of circulation is employed instead of a circulating pump, or where the circulation of water through the radiator is 90 in the opposite direction, or where a by-pass is employed for maintaining the circulation through the water jacket when circulation through the radiator is stopped, although the present invention is preferably employed 95 without a by-pass, etc.

In the embodiment of the invention shown in Fig. 2, the radiator 12 is provided with the usual vent and overflow pipe 16, and with an inlet nipple 17 with which communicates the upper water line conduit 11. As usual, the radiator is provided with a filler opening at the top thereof, and in the form shown said filler opening is provided by means of a sleeve 18 suitably secured in an 100 opening 19 in the top of the radiator. Said sleeve extends interiorly of the radiator to 105 form a casing for the thermostatically-operated valve mechanism, as shown, and extends exteriorly of the radiator to form the filler 110

opening 20, where it is threaded to receive any suitable filler cap 21, which may also, if desired, be pivotally attached to the portion 20 in any suitable way, as is common in the art. Said sleeve 18 is provided with a lateral opening 22 in which the inlet nipple 17 is suitably secured, as by solder, and with an end opening 23 which may constitute a valve port or which may be designed to receive the valve mechanism as hereinafter described. Said sleeve 18 is also shown as provided interiorly of the same with a ledge or shoulder 24 to support the valve mechanism, and with a suitable number of openings 25 so that the radiator may be filled through these openings when the radiator cap 21 is removed. Preferably the openings 25 are located above the support for the thermostatically-operated valve mechanism so that the radiator may be filled without removing the valve mechanism.

Mounted within the sleeve 18 is a thermostatically-operated valve mechanism of any suitable character and supported therein in any suitable way. In the form shown, the thermostatically-operated valve mechanism is designed to rest on the ledge 24 and is retained thereon against displacement by a suitably shaped extension 26 on the filler cap 21. If desired, however, the thermostatically-operated valve mechanism, may be threaded into the sleeve 18 or mounted therein in any other suitable way. In the form shown, the thermostatically-operated valve mechanism is so constructed as to have a sliding fit in the aperture 23 and the valve port is formed in the valve mechanism structure, but if desired the valve mechanism may be threaded into the opening 23, or otherwise mounted therein, or the valve mechanism may be so designed as to utilize the opening 23 as the valve port.

The thermostatically-operated valve mechanism may employ a thermostat of any suitable character, that shown being of substantially the same construction as disclosed and claimed in the application of Jean V. Giesler, Serial No. 145,340, filed October 30, 1926, for thermostatically controlled valve mechanism. Said mechanism includes a generally cylindrical housing 27 provided with a plurality of slots or openings in its lateral wall so as to permit free circulation of the cooling medium therethrough. Said housing at its inner end is provided with an integral valve seat flange 28 in which is formed the valve port 29. Said inner end also carries an integral spider 30 which is formed centrally of the valve port 29 into a hub 31 to guide the movement of the valve stem 32, and also preferably limit the extent of expansion of the thermostat 33. Said thermostat is shown as formed by a deeply-corrugated, highly-flexible tubular wall, preferably of resilient metal, provided with a movable end wall 34 to which is suitably secured the valve stem 32 and, at its opposite end, fixedly attached to the end wall 35 of the housing 27, said end wall 35 being preferably detachably connected to the housing 27 and carrying a boss 36 into which is threaded a boss on the stationary end wall of the thermostat, all as fully disclosed in the aforesaid application of Jean V. Giesler—although it is to be expressly understood that any other suitable form of thermostatically-operated valve mechanism and mounting structure therefor may be employed if desired. Valve stem 32 has a valve disk 37 suitably attached thereto, as by a threaded connection, which valve disk is designed to seat on the valve seat provided by the flange 28 when the thermostat is contracted, and to move away from said seat and open the valve port 29 when the thermostat is expanded, the extent of the expansion being preferably limited by the engagement of an enlargement 38 on the valve stem with the inner end of the hub 31.

When the thermostat is contracted and valve disk 37 is held against its valve seat 28, circulation of cooling medium through the radiator is prevented, except for such slight circulation as may be maintained through a suitable bleeder opening in order that the thermostat may be subjected to water of a temperature proportional to that in the engine jacket. When the water reaches that temperature at which the thermostat is designed to expand, the valve disk 37 is removed from its valve seat by the expansion of said thermostat and circulation is maintained through the cooling system, the pump, in the form shown, withdrawing the cooling medium from the radiator and forcing the same through the engine jacket and upper water line to the inlet of the radiator, where it may flow through the inlet nipple 17 into the sleeve 18, through the apertures in the housing 27, through the valve port 29, and into the radiator. The extent of circulation is controlled by the extent of opening of the valve, which in turn is determined by the thermostat in its response to the temperature of the cooling medium.

The thermostat is preferably of the volatile fluid type, and may be charged at a pressure below that to which it is normally subjected exteriorly when contracted, so that upon the occurrence of a leak it will expand, owing to its inherent resiliency or the action of a spring thereon, to open the valve port wide and maintain the maximum circulation through the cooling system, or this opening of the valve upon the failure of the thermostat may be aided or caused by the unbalanced pressure in the cooling water induced by the circulating pump by a suitable design of the valve disk and thermostat areas.

It will therefore be perceived that the thermostatically-operated valve mechanism may be positioned within the filler opening of the radiator, either in the original installation 5 of the radiator or in radiators already in service, and this without respect to whether or not the under-hood design is such as to enable the installation of thermostatically-operated valve mechanism without redesign. Therefore the present invention 10 enables the use of thermostatically-operated valve mechanism in constructions which could not heretofore use such mechanism without modification of the structure, and it also enables the use of such mechanism, in 15 systems already in service, without cutting the water line in order to install the valve mechanism.

It will also be observed that the present 20 invention does not interfere with the use of any of the common forms of filler caps, nor does it prevent the use of mechanism of the character commonly installed in the filler opening for indicating the temperature of 25 the cooling medium, because the openings provided for the admission of water permit access to the filler opening of the heated air or steam which is effective in causing such indicators to show the temperature or condition 30 of the cooling system.

While the embodiment of the invention illustrated on the drawing has been described with considerable particularity, it is to be expressly understood that the invention 35 is not restricted thereto, as the same is capable of receiving a variety of mechanical expressions, some of which will now readily suggest themselves to those skilled in the art, while changes may be made in the details of construction, arrangement and proportion of parts without departing from the spirit of this invention. Reference is therefore to be had to the claims hereto appended for a definition of said invention.

45 What is claimed is:

1. In a cooling system for internal combustion engines, in combination with a radiator provided with a filler opening, a thermostatically-operated valve mechanism insertible into the radiator through the filler opening and adapted to determine the circulation of water through the radiator.

2. In a cooling system for internal combustion engines, in combination with a radiator provided with a filler opening, a thermostatically-operated valve mechanism insertible into the radiator through said filler opening and adapted to prevent circulation of the cooling medium through said radiator 60 when the cooling medium is below a predetermined temperature.

3. In a cooling system for internal combustion engines, in combination with a radiator provided with a filler opening, a casing 65 within the radiator communicating with

said filler opening and with the inlet to the radiator, and a thermostatically-operated valve mechanism mounted in said casing and insertible therein through said filler opening for controlling the circulation of 70 cooling medium through the radiator.

4. In a cooling system for internal combustion engines, in combination with a radiator provided with a filler opening, a casing within the radiator communicating with 75 said filler opening and with the inlet to the radiator, said casing having an aperture through which the cooling medium from the inlet enters the body of the radiator, and a thermostatically-operated valve mechanism 80 mounted in said casing and adapted to close said opening when the cooling medium is below a predetermined temperature.

5. In a cooling system for internal combustion engines, in combination with a radiator provided with a filler opening, a casing within said radiator below said filler opening, an inlet for the radiator communicating with the radiator only through said casing, and a thermostatically-operated valve 85 mechanism in said casing insertible through said filler opening and controlling the flow of cooling medium out of said casing.

6. In a cooling system for internal combustion engines, in combination with a radiator provided with a filler opening, a casing in said radiator below said filler opening, an inlet for the radiator communicating therewith only through said casing, said casing having an outlet opening 100 through which the cooling medium flows into the body of the radiator, and a thermostatically-operated valve mechanism in said casing insertible through the filler opening and controlling the outflow through 105 said opening.

7. In a cooling system for internal combustion engines, in combination with a radiator provided with a filler opening, a casing in said radiator communicating with said 110 filler opening and with the inlet to the radiator, and a thermostatically-operated valve mechanism insertible through said filler opening into said casing as a unit and cooperating with said casing to control the circulation through the radiator, said thermostatically-operated valve mechanism including a thermostat, a housing for the thermostat providing a valve seat, and a valve disk connected to said thermostat and co-operating with said valve seat.

8. In a cooling system for an internal combustion engine, in combination with a radiator, a sleeve mounted in the top of the radiator and constituting a filler opening therefor, a connection between said sleeve and the inlet to the radiator, and a thermostatically-operated valve mechanism mounted in said sleeve and controlling the circulation through said radiator.

9. In a cooling system for an internal combustion engine, in combination with a radiator, a sleeve mounted in the top of the radiator and constituting a filler opening therefor, a connection between said sleeve and the inlet to the radiator, said sleeve being provided with an outlet aperture, and a thermostatically-operated valve mechanism mounted in said sleeve and controlling the outflow of the cooling medium through said aperture.
10. In a cooling system for an internal combustion engine, in combination with a radiator, a sleeve mounted in the top of the radiator and constituting a filler opening therefor, a connection between said sleeve and the inlet to the radiator, said sleeve having apertures through which the body of the radiator communicates with said filler opening, and a thermostatically-operated valve mechanism mounted in said sleeve below said apertures and controlling the circulation of the cooling medium through the radiator.
11. In a cooling system for an internal combustion engine, in combination with a radiator, a sleeve mounted in the top of the radiator and constituting a filler opening therefor, a connection between said sleeve and the inlet to the radiator, said sleeve having an outlet aperture at its inner end and apertures of communication between the body of the radiator and filler opening adjacent its outer end, and a thermostatically-operated valve mechanism mounted in said sleeve below said last-named apertures and adapted to control the flow of cooling medium through said first-named aperture.
12. In a cooling system for an internal combustion engine, in combination with a radiator provided with a filler opening, a thermostatically-operated valve mechanism mounted in the radiator and insertible as a unit into the radiator through said filler opening.
13. In a cooling system for an internal combustion engine, in combination with a radiator provided with a filler opening, a thermostatically-operated valve mechanism mounted in unitary relationship with the radiator, said thermostatically-operated valve mechanism comprising a thermostat, a housing therefor providing a valve seat, and a valve member connected to said thermostat and cooperating with said seat, said thermostat, housing and valve member constituting a unit readily insertible into the filler opening of said radiator.
14. In a cooling system for an internal combustion engine, in combination with a radiator having a filler opening and a filler cap therefor, and a thermostatically-operated valve mechanism mounted in said radiator and insertible through said filler opening, said thermostatically-operated valve mechanism being held against displacement by said filler cap.
15. In a cooling system for an internal combustion engine, in combination with a radiator having a filler opening and a filler cap therefor, a casing within the radiator communicating with said filler opening and with the inlet to the radiator, and a thermostatically-operated valve mechanism insertible into said casing through said filler opening, said casing having means cooperating with said thermostatically-operated valve mechanism for supporting the same within said casing and said filler cap, cooperating with said mechanism to retain the same on its support.

In testimony whereof I have signed this specification.

JAMES A. KINNARD.
